FRICTION DEVICE FOR VERTICALLY
SLIDING WINDOW SASHES

Louis A. Macklanburg, Oklahoma City, Okla.

Application April 5, 1944, Serial No. 529,888

2 Claims. (CL 292—76)

My invention relates to devices for providing friction between a window frame and a vertically slideable sash mounted therein.

During recent years, considerable effort has been exerted, by window frame and sash manufacturers, in an attempt to eliminate the use of sash pulleys, sash cords and sash weights, which are normally used to counter-balance the weight of the sash. Sash weights as commonly used at the present time, not only act to overcome the friction between the sash and frame, and thereby reduce the effort required to raise a window sash, but by counter-balancing the weight of the sash, they also act to hold it in any desired position of vertical adjustment. It has been found that counter-balance sash weights could well be eliminated, in connection with window frames wherein comparatively light weight sliding sash are used, were it not for the fact that the sash, due to its weight, will not remain in the various desired positions of vertical adjustment.

In order to hold the sash in such desired vertical positions, blade spring members of various configurations have heretofore been employed between the edge of the sash and the face of the window frame. It has been found, however, that springs having different resiliency must be provided for sashes of each different weight, even when the clearance between the window frame and the edge of the sash is made uniform. However, since such clearance is not always made uniform, various friction springs, having different amounts of resiliency, must be tried before the correct amount of friction can be obtained. This means that the person making the sash installation must first equip himself with an assortment of springs of different sizes or thickness, and he must then experiment until he finds the proper springs for each particular sash installation.

The prime object of the present invention is to provide a friction exerting spring, for the purpose set forth, and to provide, in connection therewith, an adjustable means whereby the spring may be adjusted to compensate for sashes of different weights, and also to compensate for the different clearance spaces between the sash and frame.

Another object is to provide a device of this class which is simple in construction, and therefore comparatively cheap to manufacture.

A further object is to provide a device of this class wherein the adjustment may be easily and quickly accomplished.

It is a still further object of the present invention to provide a facing strip for window frame sash races, or for the outer edges of vertically

sliding window sash, which strip will co-act with friction springs of the type described for impeding gravitational movement of the sash.

Other objects will be apparent from the following description when taken in connection with the accompanying five sheets of drawings, wherein:

Figure 1 is a fragmentary vertical sectional view of a window frame, the full lines showing one embodiment of the friction spring member operatively installed thereon, and the dotted lines illustrating its adjustability;

Figures 2 and 3 are similar views of two slightly different embodiments of the spring member;

Figure 4 is a fragmentary vertical sectional view through a vertically sliding window sash, and showing in a similar manner, another embodiment of the friction spring operatively installed thereon;

Figure 5 is a view similar to that of Figure 4, and showing yet another embodiment of the spring member of the present invention;

Figure 6 is a fragmentary perspective view of a typical window frame with two vertically sliding sashes operatively mounted therein, a portion of 25 the side rail of each sash being broken away to disclose the friction spring of Figure 1 operatively disposed on the window frame;

Figure 7 is a fragmentary perspective view of a typical window frame, with two vertically sliding sashes mounted therein, and showing the friction spring of Figure 4 operatively installed on the outside face of a side rail of each sash;

Figure 8 is a view similar to Figure 3, showing a slightly different arrangement of the friction spring attached to a window frame member;

Figure 9 is a view similar to Figure 8 showing the spring of Figure 8 operatively installed upon the outside edge of a window sash;

Figure 10 is a view similar to Figure 7 illustrating a friction plate or strip operatively installed in a window frame sash race;

Figure 11 is a fragmentary front elevational view of a typical window frame, a portion of the trim being broken away to illustrate the co-acting 45 function of the spring and strip;

Figure 12 is a view similar to Figure 10 showing the friction strip thereof operatively installed upon the vertical outside edge of the window sash;

Figure 13 is a view similar to that of Figure 11 but showing the co-action of the friction strip of Figure 12 with a friction spring mounted in a sash race; and,

Figure 14 is a fragmentary perspective view of a slightly different embodiment of the friction strip.

In the drawings:

The reference numeral 1 indicates a portion of a vertically extending side member of a usual window frame, the inside surface of which is indicated by the numeral 2. The surface 2 is that face of the frame member 1 along which the outer edge of a vertically sliding window sash usually slides. The friction spring elements of Figures 1, 2, and 3 are designed to be operatively installed upon the face 2, in the sash race which is formed between the usual parting stop 3 and a blind stop 4, (Figures 6 and 7), or is installed in the sash race lying between the parting stop 3 and a molding stop 5. Ordinarily the springs will be mounted in both races so as to contact each outermost edge of the two side rails 6 of the upper sash 7 and the similar edges of the side rails 8 of the lower sash 9.

Referring now more particularly to Figure 1, the reference numeral 10 indicates, as a whole, a comparatively thin resilient metal spring of the strap or blade type. The spring 10 is formed from a single piece, and is properly tempered after being formed. The spring 10 is transversely corrugated to provide three waves or crests 11, 12, and 13, and to form two valleys 14 and 15. The middle crest 12 is of less extent from the surface 2 of the window frame than the crests 11 and 13 which respectively lie above and below the crest 12, and the valley portions 14 and 15 connect the wave 12 to the waves 11 and 13 respectively. The valleys 14 and 15 rest against the surface 2 and are held in contact therewith by a wood screw 16, or other suitable detent. The upper and lower portions of the waves 11 and 13 respectively terminate in lips 17 and 18 which project slightly away from the surface 2.

As clearly illustrated by the dotted lines, tightening of the screw 16 toward the surface 2 acts to reduce the extent of the wave 12, and the extent of the crests 11 and 13 are thereby increased. It is obvious that greater friction will therefore be exerted on the edge of the sash.

It is pointed out that the amount of the curvatures of the spring 10 have been exaggerated in Figure 1, as well as in Figures 2, 3, 4 and 5, in order to better illustrate the principle of the friction adjustment feature. It will also be understood that the presence of the window sash, when the spring is in actual use, will materially decrease the amount of extension of the curvatures from the surface 2 of the window frame.

In Figure 2 there is illustrated a friction spring 20 which is formed somewhat similar to the spring 10, but is different in that its upper and lower end portions 21 and 22 do not normally contact the face 2 of the frame when the sash is absent. The spring 20 is identical with the spring 10 of Figure 1 except that the lips 17 and 18, and the end portions of the waves 11 and 13 have been severed and the remaining ends are turned in toward the surface 2 as shown at 23. The adjustment of this embodiment of the invention is accomplished in a manner similar to that of the spring 10 of Figure 1.

In Figure 3 is shown an adjustable friction spring 30 formed out of a strip of flat spring metal. This spring has two end lips 31 and 32, similar to the lips 17 and 18 of Figure 1. It has two valleys 33 and 34 and two sloping sides 35 and 36 which extend outwardly from the surface 2 and converge to form a pocket or countersink portion 37 for nesting the head of the wood screw 16. In this embodiment, movement of the screw head toward the face 2 of the window frame

decreases the amount of friction which the spring may exert against the edge of the sash.

In Figure 4 is illustrated an embodiment of the invention which is designed to be mounted upon the outer edge of the vertical side member of a sliding window sash. This side member is indicated by the reference numeral 40, and has an outer surface 41 which normally contacts the face 2 of the window frame.

In this embodiment, the side member 40 is laterally bored to receive a tubular ferrel 42 having interior threads 43 throughout its length. An exteriorly threaded cylindrical adjusting element 44 is threadededly engaged with the threads 43 within the ferrel 42, and has a slot across one end to receive a screw-driver for an obvious reason. The opposite end of the element 44, carries an axial pin 45 which extends outwardly from the ferrel 42 beyond the surface 41 of the member 40, and its outer end is provided with a head 46.

In this embodiment, there is provided a friction spring 47 which is similar in figuration to the spring 20 of Figure 2. Adjustment of the element 44 within the ferrel 42 has the same effect in this embodiment, as does adjustment of the wood screw 16 of Figure 2 upon the spring 20.

In Figure 5, the adjusting mechanism is the same as in Figure 4, but a friction spring 50 is used in lieu of the spring 47 of Figure 4. The spring 50 is shaped similarly to the spring 30 of Figure 3, except that instead of the counter sunk portion of 30, there is provided a valley 51 to receive and nest the head 46 of the pin 45. Movement of the adjusting element 44 in Figure 4 has the same effect upon the spring 50 as does adjustment of the wood screw 16 of Figure 3.

In Figure 6, is shown the positions in the window frame at which the friction springs should be installed, and in Figure 7 two of the springs 47 of Figure 4 are shown operatively installed upon a vertically sliding window sash. In Figures 6 and 7 the installation of only the springs 10 and 47 have been shown, but the other types of springs could well be used in lieu of them.

In Figure 8 there is shown a friction spring 30, of the type illustrated in Figure 3, installed upon the surface 2 of the window frame 1 by a slightly different adjusting means. In this embodiment the frame member 1 of the window frame is provided with a horizontal through bore 60. A threaded plate 61 is provided along the outside surface 62 of the member 1, and has a threaded perforation for receiving a stove bolt 63. The bolt 63 is used similarly to the wood screw 16 of Figure 3 with its head 64 nested in the counter-sink 37 of the spring 30.

The advantage of this type of installation lies in the fact that the head 64 of the bolt 63 always lies within the transverse bore 60 in the frame member 1. This precludes any possibility of the head 64 ever contacting the edge surface of a window sash, no matter how closely the sash may fit in the window frame. In this embodiment the friction of the spring 30 is adjusted by use of a screw-driver, before the sash is placed in its sash race.

In Figure 9, the spring 30 is shown installed upon the outer vertical edge surface of the side member 40 of a window sash. In this embodiment, a pocket 70 is provided in the outer edge face of a window sash, in order to allow the central portion 37 of the spring to operate therein. A stove-bolt 71 extends outwardly through the sash member 40, and a wing-nut 72 is provided

upon its outer end for adjusting the spring 30 in an obvious manner.

In some cases, such as in factory windows, it has been found that vibration of machinery, trains, etc., will tend to let a raised window sash gradually work downwardly, even though the tension of the various friction springs is sufficient to normally hold the sash stationary. To prevent such a contingency, transversely ribbed friction strips may be used in conjunction with the various friction springs above described herein. These strips and their positions of installation are illustrated in Figures 10, 11, 12, 13 and 14.

The friction strip is indicated by the reference numeral 80, and consists of a strap-like element, preferably of sheet metal, having a plurality of spaced self formed transversely extending ribs 81. The strip 80 may be installed in the window frame sash races as illustrated in Figures 10 and 11 in cases where the friction springs are carried by the window sash. When the friction springs are mounted in the sash races, the strips 80 will then be installed along the outer vertical edge surfaces of the sash, as illustrated in Figures 12 and 13. In Figures 10, 11, 12 and 13, the ribs 81 are shown to be spaced to coincide properly with the portions 11 and 13 of the spring 47, but this spacing could be varied as desired. With the ribs 81 spaced substantially like those of Figure 14, practically any one of the friction springs would be accommodated.

It is thought to be evident that the ribs 81 of the strips 80 do not offer sufficient resistance

against movement of the sash to vitally impair manual raising or lowering of the same. The springs will ride over the ribs when sufficient pressure is applied.

5 I claim:

1. In a device of the class described, the combination with a vertically disposed window frame member having a race for receiving the edge of a vertically slidable window sash, said member having an indentation in its race, of: a blade-type spring having a central portion adapted to nest within said indentation, said portion being of a depth less than the depth of said indentation; other portions of said spring, one at each side of said central portion, and normally spaced from the surface of said race; and means for adjustably moving said central portion of the spring toward the bottom of said indentation.

2. In a device of the class described, the combination with a vertically disposed member of a vertically sliding window sash, said member having an indentation in its outer side edge surface, of: a blade-type spring having a central portion adapted to nest within said indentation, said portion being of a depth less than the depth of said indentation; other portions of said spring, one at each side of said central portion, and normally spaced from the edge surface of said sash; and means for adjustably moving the central portion of said spring toward the bottom of said indentation.

LOUIS A. MACKLANBURG.
